RECEPTACLE AND CLOSURE

William Lockhart, Cleveland, Ohio, assignor to
 Cornell Securities Corporation, Cleveland, Ohio,
 a corporation of Delaware

Application May 2, 1935, Serial No. 19,440

7 Claims. (Cl. 220—61)

My invention is an improvement in metallic receptacles and closures therefor and relates more particularly to a clamping ring for removably clamping the cover on the receptacle in fluid tight sealed relation thereto.

One of the objects of my invention is to removably clamp a cover upon a receptacle by providing a split contractible channeled clamping ring to engage the cover and receptacle and press the same together in fluid tight sealed relation and means for contracting the ring to this end.

Another object is to provide means for contracting and/or expanding the ring including one or more levers having slideable engagement with the ring ends and means positively connecting said levers where a plurality are used, or connecting one lever and an end of the ring where a single lever is employed.

A further object is to exert a lateral pressure against the cover flange by said lever or levers when they are operated to contract the ring and to thereby more uniformly distribute the closing forces exerted by the ring on the cover around the same.

Other objects are the simplicity of the device, its low cost of manufacture and its ease of operation.

Other objects and advantages of the invention will become more apparent from the following description of two embodiments thereof, reference being made to the accompanying drawing in which like reference characters are employed to designate like parts throughout the same.

In the drawing:—

Figure 1 is a top plan view of one embodiment of my invention shown applied in use;

Figure 2 is an enlarged section taken on line 2—2 of Figure 1;

Figure 3 is a fragmentary plan view of the first embodiment of the invention and shows the parts in their respective positions when the ring is fully contracted to seal the cover on the receptacle in fluid tight relation;

Figure 4 is a view similar to that shown in Figure 3, and shows the positions of the parts when the ring is expanded to remove it and the cover from the receptacle;

Figure 5 is an enlarged elevation looking in the direction of line 5—5 of Figure 3; and,

Figure 6 is a view similar to that shown in Figure 3 and illustrates a second embodiment of the invention in which but one lever is employed.

Referring now more particularly to the drawing, the barrel or drum is indicated at 1. The upper open end of the container is formed with a

peripheral bead 2. A cover 3 comprising a cupped or depressed head, having a peripheral upwardly and outwardly extending flange 4, is supported by the bead 2 in such a manner that the cupped portion of the head or cover may be telescoped for a short distance within the open end of the drum, as illustrated in Figure 2. It will be noted that a portion of the flange 4 is of substantially arcuate cross section to conform with the approximate curvature of the upper surface of the bead. 10 A packing 5 consisting of an annulus of any suitable packing material, such as flexible rubber tubing or cork, is interposed between the flange 4 and the bead 2.

According to the present invention, I have provided an improved means for removably securing the cover on the drum or receptacle to effect a fluid tight seal therebetween by exerting a substantially uniform and firm pressure along the cover flange and bead in a direction substantially parallel to the longitudinal axis of the drum.

Such means preferably includes a transversely split, channeled clamping ring 6 of substantially U-shaped cross section and which is capable of being expanded and contracted by suitable means. 25 In the form illustrated the upper and lower flange and bead engaging walls respectively of the ring converge slightly toward the outer diameter of the ring and engage the cover flange and bead of the container to press the same together tightly when the ring is contracted. However, it is to be understood that the ring and receptacle open end may be so designed that the cover will be pressed into a tight seal with a shoulder formed at the receptacle open end when the ring is expanded. 30 That is, instead of the receptacle being formed with a rolled bead 2, the open end may be formed with an annular shoulder and an annular channel for receiving an expander type ring, a packing ring and the cover.

By contracting the type of clamping ring herein illustrated, the cover flange will be pressed tightly against the packing 5 and the supporting bead 2 under a substantially vertical pressure.

Referring first to Figures 1 to 5 inclusive, I have illustrated one embodiment of the invention in which the operating mechanism includes a pair of levers having slideable pivotal connection with the ends of the ring or with brackets or lugs extending from these ends. The levers are also 50 connected together by means of a link or bridging member.

More specifically, the ends of the ring 6 are provided with inwardly extending lugs or brackets 7 and 8 respectively, welded thereto or formed 55

integral therewith. The ring contracting and expanding levers 9 and 10 are enlarged at their fulcrumed ends as at 11 and 12 and are slotted at 13 and 14 respectively to slidably receive bearing members or studs 15 and 16 carried by the lugs or brackets 7 and 8 respectively. The studs may be equipped with roller bearing sleeves (not shown) to minimize the friction between them and the walls of the slots. It is to be noted that the slots are curved and may generally be arcuate in shape. Spiral, involute or other curves may define the slots 13 and 14 if desired.

Thus the levers 11 and 12 are slidably and pivotally connected to the respective lugs 7 and 8. The levers are also pivotally connected together at 17 and 18 by means of a bridging member 19. The member 19 is preferably a flat strip of metal and is upset at its ends 20 and 21 to provide an intermediate offset portion.

The curved slots 13 and 14 extend inwardly from the inner ends of the levers and traverse substantially the enlarged fulcrumed ends of the levers, and while I have shown both the slots 13 and 14 of substantially the same curvature, one of the slots may be formed along longer or shorter radii. In this manner the individual throws of the levers may be varied. For instance, the radius of the slot 14 may be longer than that of the slot 13. Thus by first swinging the lever 9 to closed position as in Figure 3 a certain degree of contraction will be imparted to the ring which may be sufficient to hold the cover in place for shipping the drum empty. But by subsequently swinging the lever 10 to closed position, as in Figure 3, the longer radius of the slot 14 will impart an even greater degree of contraction to the ring sufficient to press the cover and receptacle together in fluid tight sealed relation. In the particular embodiment shown, however, the slots are formed on substantially equal radii, but the radii are of sufficient length to impart a fluid tight seal when both levers are moved to ring contracting position.

The lever ends 11 and 12 are provided with a cam-like bearing surface 22 and 23 respectively for engagement with the upwardly extending portion of the cover flange 4 to exert an outward radial pressure thereagainst when the levers are moved to the position shown in Figure 3. This outward pressure materially aids in properly seating the ring on the cover and receptacle by more uniformly distributing the closing forces around the ring as the ring is contracted.

In Figure 6 I have illustrated a modified embodiment of the invention in which a single lever 30 is employed. In this form of the invention the lever 30 is slidably and pivotally connected with one of the lugs 7 by means of the stud 31 carried by the lug and operating in the curved slot 32 in the fulcrumed end of the lever. The lever is pivotally connected with the other end of the ring or the lug 8 by means of a link 33 pivoted to the lever at one end as at 34, and at its other end to the lug 8, as at 35.

While I have described the illustrated embodiments of my invention in some particularity, obviously many others will readily occur to those skilled in this art, and I do not, therefore, limit myself to the precise details shown and described but claim as my invention all embodiments, variations and modifications thereof coming within the scope of the appended claims.

I claim:

1. A device for removably clamping a cover on the open end of a metallic receptacle including a

split locking ring having portions engaging the cover and the receptacle to press the same together when the ring is contracted, lugs extending inwardly from the ends of the ring defining the split and means for contracting and/or expanding the ring, said means, including a lever, having an arcuate bearing formed therein near one end, a member carried by one of said lugs and having a driving connection with said lever through the bearing, and a toggle pivotally connected with said lever and said other lug. 5 10

2. A device for removably clamping a cover on the open end of a metallic receptacle including a split locking ring having portions engaging the cover and the receptacle to press the same together when the ring is contracted, lugs extending inwardly from the ends of the ring defining the split and means for contracting and/or expanding the ring including levers slidably carried by said lugs, one of said levers having a 20 slot formed therein for slidably receiving a stud, a stud on one of said lugs and operating in said slot, and a toggle pivotally connecting said levers.

3. A device for removably clamping a cover 25 on the open end of a metallic receptacle including a split locking ring having portions engaging the cover and the receptacle to press the same together when the ring is contracted, lugs extending inwardly from the ends of the ring defining the split and means for contracting and/or expanding the ring including a lever, a 30 stud in one of said lugs, said lever having a closed slot formed therein for receiving said stud whereby to permit a limited relative sliding driving connection between the said one lug and said lever, and a toggle pivotally connecting said lever with said other lug. 35

4. A device for removably clamping a cover on the open end of a metallic receptacle including 40 a split locking ring having portions engaging the cover and the receptacle to press the same together when the ring is contracted, lugs extending inwardly from the ends of the ring defining the split and means for contracting and/or expanding the ring including a lever carried by 45 one of said lugs and having a slideable pivotal connection with said lug whereby the fulcrum of said lever may be shifted, and means cooperating with said lever and the other of said lugs for 50 effecting contraction and/or expansion of said ring, said lever having engagement with said cover to impart an outward radial pressure against the cover when the ring is contracted.

5. A device for removably clamping a cover on 55 the open end of a metallic receptacle including a split locking ring having portions engaging the cover and the receptacle to press the same together when the ring is contracted, lugs extending inwardly from the ends of the ring defining 60 the split and means for contracting and/or expanding the ring including levers slidably carried by said lugs and a toggle pivotally connecting said levers, one of said levers having a portion engaging with said cover to impart an outward 65 pressure against the cover when the ring is contracted.

6. A device for removably clamping a cover on the open end of a metallic receptacle including a split locking ring having portions engaging the 70 cover and the receptacle to press the same together when the ring is contracted, lugs extending inwardly from the ends of the ring defining the split and means for contracting and/or expanding the ring including levers slidably carried 75

5 by said lugs, one of said levers having a slot formed therein for slidably receiving a stud, a stud on one of said lugs and operating in said slot, and toggle means pivotally connecting said levers, one of said levers having a portion for engagement with said cover to impart an outward pressure against the cover when the ring is contracted.

10 7. A device for removably clamping a cover on the open end of a metallic receptacle including

a split locking ring having portions engaging the cover and the receptacle to press the same together when the ring is contracted, lugs extending inwardly from the ends of the ring defining the split and means for contracting and/or expanding the ring including levers slidably carried by each of said lugs and means cooperating with each of said levers for effecting contraction and/or expansion of said ring.

WILLIAM LOCKHART. 10
